PORTABLE BARBECUE GRILL

James L. Hoff, Maple Plain, Minn., assignor to West Creek Co., Inc., Minnetonka, Minn.

Filed Mar. 26, 1970, Ser. No. 22,062

Term of patent 14 years

Int. Cl. D7—04

U.S. Cl. D81—10

FIG. 1

FIG. 2

FIG. 3

FIG. 5

FIG. 4

FIG. 1 is a perspective view of a portable barbecue grill embodying my new design;

FIG. 2 is a top plan view thereof;

FIG. 3 is a side elevational view thereof;

FIG. 4 is a bottom plan view thereof; and

FIG. 5 is a sectional view thereof taken as on line 5—5 in FIG. 2.

I claim:

The ornamental design for a portable barbecue grill, substantially as shown.
